UNITED STATES PATENT OFFICE

161,639

CABINET FOR AN ELECTRIC PRINTING MACHINE

William Richard Harding Moon, London, England, assignor to Adrema Limited, London, England, a British company

Application June 2, 1949, Serial No. 3,002
In Great Britain May 5, 1949

Term of patent 14 years

(Cl. D64—11)

To all whom it may concern:

Be it known that I, William Richard Harding Moon, a British subject residing at London, England, have invented a new, original, and ornamental Design for a Cabinet for an Electric Printing Machine, of which the following is a specification, reference being had to the accompanying drawing, forming part thereof.

Fig. 1 is a perspective front view of a cabinet for an electric printing machine, showing my design, and

Fig. 2 is a perspective rear view of the cabinet for an electric printing machine according to my design.

I claim:

The ornamental design for a cabinet for an electric printing machine, substantially as shown.
WILLIAM RICHARD HARDING MOON.
